United States Patent Office

Des. 179,282
Patented Nov. 27, 1956

179,282

HOUSE NUMBER SIGN

Walter A. Curtze, Erie, Pa.

Application November 23, 1954, Serial No. 33,202

Term of patent 3½ years

(Cl. D1—12)

FIG. 1

FIG. 2

Fig. 1 is a front view of the house number sign showing my new design; and Fig. 2 is a perspective of the house number sign from the back.

The broken lines are for illustrative purposes only.
I claim:

The ornamental design for a house number sign, substantially as shown and described.
